CLAIM

I claim the ornamental design for a table leg, as shown and described.

DESCRIPTION

FIG. 1 is a perspective view of the first embodiment of a table leg shown in an environment of use, showing my new design;

FIG. 2 is a right top perspective view of the first embodiment of a table leg;

FIG. 3 is a left top perspective view thereof;

FIG. 4 is a front view thereof;

FIG. 5 is a back view thereof;

FIG. 6 is a right side view thereof;

FIG. 7 is a left side view thereof;

FIG. 8 is a top view thereof;

FIG. 9 is a bottom view thereof;

FIG. 10 is a perspective view of the second embodiment of a table leg shown in an environment of use;

FIG. 11 is a right top perspective view of the second embodiment of a table leg;

FIG. 12 is a left top perspective view thereof;

FIG. 13 is a front view thereof;

FIG. 14 is a back view thereof;

FIG. 15 is a right side view thereof;

FIG. 16 is a left side view thereof;

FIG. 17 is a top view thereof; and,

FIG. 18 is a bottom view thereof.

The broken line portion of the figure drawings is included to show environment and boundaries of the article that form no part of the claimed design. The article is shown with a symbolic break in its length. The appearance of any portion of the article between the break lines forms no part of the claimed design.

1 Claim, 14 Drawing Sheets
